ELECTRIC COMPUTER

David M. Boyd, Jr., Clarendon Hills, Ill., assignor to Universal Oil Products Company, Des Plaines, Ill., a corporation of Delaware

Application December 31, 1954, Serial No. 478,971

2 Claims. (Cl. 235—61)

This invention relates to an electric computer for simultaneously solving inter-related equations and in particular to an electric computer especially adapted to making tray by tray temperature and composition calculations for designing fractionation or other multi-stage equipment.

Many problems in engineering and research require the solution of long, complex series of inter-related mathematical equations in order to arrive at a proper design for equipment or to determine the course of a reaction. Frequently, in the solution of these equations each stage of solution depends upon the solution of the last previous stage so that an ultimate answer to the problem is difficult to obtain in a short period of time since the various parts of the problem cannot be worked on independently by several people. Typical of these problems are those associated with the design of multi-stage equipment such as fractionation columns, multiple effect evaporators, liquid-liquid or liquid-solid extraction processes, etc. The design of the equipment for these processes requires long hours of routine work which must be accomplished by highly trained men who could be better used for more creative problems. The laborious manual solution of complex mathematical equations also invites human error which frequently requires recalculations to be made or alternatively incorporates mistakes into the ultimate design. It is an object of this invention to rapidly and accurately calculate such problems by electric means.

To accomplish this object it is an embodiment of this invention to provide an electric computer comprising in combination a constant voltage source connected to a plurality of identical parallel circuits, each of said circuits comprising a first voltage dividing means connected to a bank of parallel first voltage multiplying means which are adapted to be preset to specific multipliers, suitable programming means for alternately inserting pairs of consecutive first multiplying means into an interpolating balancing circuit which adds the voltages to similarly obtained voltages from the other parallel circuits and balances the circuit at said constant voltage when one of the sums of the consecutive pairs of first multiplying means causes one voltage greater and one voltage less than said constant voltage, recording means to record the position of balance of said interpolating circuit as the proportion of the difference that said constant voltage is from said greater voltage and said less voltage, second multiplying means adapted to be preset to specific multipliers connected one to a fixed voltage dividing means to multiply the fixed divided voltage and another to multiply the voltage obtained by one of the pair of the aforesaid first multiplying means, a second adding circuit connected to said second multiplying means whereby their voltages are added, balancing means connected to said second adding circuit and to a second voltage dividing means whereby the resultant sum of the voltages is balanced against said constant voltage to obtain a voltage equal to said sum from said second voltage dividing means, connecting said second voltage dividing means to a bank of parallel

2

fourth multiplying means which are adapted to be preset to specific multipliers, suitable programming means for alternately inserting consecutive pairs of fourth multiplying means into a second interpolating balancing circuit which adds the voltages to similarly obtained voltages from the other parallel circuits and balances the circuit at said constant voltage when one of the sums of the consecutive pairs of fourth multiplying means causes one voltage greater and one voltage less than said constant voltage, fifth multiplying means adapted to be preset to specific multipliers connected one to said fixed voltage dividing means to multiply the resultant fixed voltage and another to multiply the voltage obtained from one of the pairs of the aforesaid fourth multiplying means, a fourth adding circuit connected to said fifth multiplying means whereby the voltages are added, balancing means connected to said fourth adding circuit and to said first voltage dividing means whereby the sum of the voltages is balanced against said constant voltage to obtain a voltage from said first voltage dividing means equal to said sum from said voltage dividing means.

Since the apparatus and method of this invention are particularly adapted to aiding in the design of fractionation columns it will be described in relation thereto, however, it is to be understood that this choice of an example is not intended to be limiting on the apparatus or its function. Basically the apparatus of this invention consists of a series of identical parallel circuits for each component of a mixture to be fractionated. Therefore, a two component system will have two parallel circuits and a five component system will have five parallel circuits, however, some systems contain hundreds of components, for example, a petroleum fraction, and in these cases a circuit will be used for each boiling range desired instead of each component. Each of the parallel circuits representing a component or a boiling range is comprised of a voltage dividing means for establishing a voltage proportional to the desired purity of that component and a series of parallel voltage multiplying means which are programmed to function as consecutive pairs until a proper pair is in the circuit. That is multiplying means 1 and 2 will function as a pair and then multiplying means 2 and 3 will function as a pair, next 3 and 4, etc. There may be as many multiplying means in each of these banks as desired, the number being chosen in accordance with the accuracy desired.

Each parallel circuit also contains a second group of multiplying means for correcting an answer obtained in the first group for the influence of another stream.

Since the operation of this apparatus is rather complex it may be best described with reference to the accompanying drawing which illustrates an extremely simple embodiment and is not to be limiting on this invention. The drawing illustrates a circuit established to design a fractionator for a two component system that is desired to produce a 95% pure overhead from the mixture of high boiling and low boiling components. This column is to have a four to one reflux ratio, or in other words, for every five parts of overhead from the column four parts are condensed and returned to the top tray and one part is withdrawn as product. In the explanation, K is the constant (at a specific temperature and pressure) from equation

$$Y = KX$$

where Y is the mol percent of one component in the vapor phase and X is the mol percent of that component

in the liquid phase from which the vapor came, or the liquid phase in equilibrium with that vapor. E_1 is any base voltage and for the purposes of this explanation it will be considered 100 volts, however, it is understood that any voltage may be suitable. The base voltage is imposed across the circuit by connecting voltage dividing means 1, 2, 3 and 4 to a suitable source of power and to the ground. Voltage dividing means 1 and 3 are set to take a percent of the base voltage equivalent to the desired percent of light component in the product from the column. Therefore, in this example, since it is desired to have 95% purity of light material in the product, voltage dividing means 1 and 3 will be set to take 95% of the base voltage or in this case 95 volts. Thus, in lines 5 and 21 a potential of 95 volts exists. The function of line 21 will be considered later and will not be discussed further at this point.

Similarly, voltage dividing means 2 and 4 are set to establish a voltage proportional to the percent of heavy material in the overhead product and in this case, since the percent of light material and heavy material must be 100, voltage dividing means 2 and 4 are regulated to place a voltage of 5 volts or 5% of E_1 in lines 12 and 34. As with line 21 above described, a detailed discussion of line 34 will be deferred.

It is now desired to obtain the composition of the liquid on the top tray of the column from which the vapor containing 95% light material and 5% heavy material was obtained. Since K multiplied by the composition of the liquid will produce the answer Y , which is the composition of the vapor, then the composition of the vapor Y multiplied by the reciprocal of K will produce the composition of the liquid in the light material from which the vapor was obtained. Therefore, voltage multiplying means 6 is established in series with line 5 and multiplies the voltage in line 5 by

$$\frac{1}{K}$$

to produce in line 8 a voltage corresponding to the amount of light material in the liquid phase on the top tray. Similarly, the voltage in line 5 is transmitted to voltage multiplier 7 wherein it is multiplied by

$$\frac{1}{K'}$$

to produce in line 9 another voltage corresponding to the composition in light material of the liquid phase on the top tray.

Since the true K value is unknown and the K values used are incorrect, the two voltages corresponding to the liquid composition on the top tray are also not correct, however, this difficulty is overcome by the use of a series of K values and the interpolating circuit. Since it is known that the column will operate over a given temperature range and it is also known that the column will operate over a given composition range, the K value for the components of the mixture to be separated may be known for a given temperature and composition. Thus, for example, if the column operates over a 100° F. to 200° F. temperature range, K values may be set into the series of multiplying means corresponding to the K value of the components at 10° temperature increments over the temperature range of operation. The K values are arbitrarily chosen and will usually be at convenient even increments for example, at each 10°. In other words, the bank of multipliers represents a series of trials at obtaining the value K , which is a number which quantitatively describes the difference in volatility between the two components in the mixture to be separated at the temperature in the stage being calculated.

Simultaneously with the above described multiplications, the voltage in line 12 which represents the composition of the vapor in heavier material is also multiplied by suitable

$$\frac{1}{K}, \frac{1}{K'} \text{ etc.}$$

values by multipliers 13 and 14 respectively and whatever additional multipliers are in parallel with these two to establish in lines 15 and 16 respectively two values for the composition of the liquid on the top tray in heavier component. The

$$10 \quad \frac{1}{K}$$

values in this circuit which calculate the composition of heavier component in the liquid must be identical in number to the

$$15 \quad \frac{1}{K}$$

values in the previously described circuit which calculates the latter component. That is, if the first circuit has 10 values of

$$20 \quad \frac{1}{K}$$

the others must also have 10 values. It is also necessary that the

$$25 \quad \frac{1}{K}$$

values in the circuit calculating the light material be different by a proportional amount, which proportional amount represents the ratio of the K values of these two

30 components at any temperature. Therefore, if the volatility of the light component as compared to the volatility of the heavy component were such that the K value for the light component were twice the K value for the heavy component, the corresponding multipliers in the parallel

35 circuits would differ by a factor of 100% in the magnitude of their effect upon the input voltage to each of the corresponding multipliers. By making the difference in K value proportional between the light material circuit and the heavy material circuit one assumes that there is a

40 constant difference between the K values over the entire temperature range or, in other words, that the plot of K versus temperature for the two components would produce two lines whose distance apart on the graph paper would be substantially unchanged over the temperature range involved. Although this assumption is not strictly true it is usually made in calculations of fractionating columns along with assumptions of equal molal boil-up and equal molal overflow. It has been found from experience that these assumptions are substantially true and deviations from them are extremely small and ordinarily negligible compared with other quantities involved. By establishing

$$45 \quad \frac{1}{K}$$

50 values on each tray using an assumed temperature as the standard, the proportionality of the

$$60 \quad \frac{1}{K}$$

values is automatically set. It is of course necessary that the

$$65 \quad \frac{1}{K}$$

70 value selecting mechanisms for the two parallel circuits coact so that the same pair of values is in the two circuits at the same time.

The voltages established in lines 8 and 15, which represent the composition of the liquid on the top tray in light material and in heavy material are connected to adding circuit 10 which produces in line 17 the sum of these voltages. As hereinbefore stated the amount of heavy material plus the amount of light material, percentage-wise, should equal 100%, or in this case 100 volts. However, since the K values are arbitrarily chosen

the sum of the products will probably not be 100 volts or E_1 , but a voltage E_2 which will probably be greater than or less than E_1 . If the value of E_2 is equal to the value of E_1 , then of course the problem of the top tray liquid composition and temperature is solved and the arbitrarily chosen K value is correct, however, if it is not equal to E_1 further calculations must be made and these are made by adding the voltages established in lines 9 and 16, which are equivalent to a second calculation of composition of heavy and light material in the liquid phase on the top tray. This addition is performed by adding circuit 11 which produces in line 18 a voltage E_3 which will be different from E_2 .

It is desired that if E_2 and E_3 are neither equal to E_1 , one of them is higher than E_1 and one of them is lower than E_1 . When this situation exists E_2 and E_3 through lines 17 and 18 respectively, are placed at opposite ends of interpolating circuit 19 which establishes the distance between them that is proportional to E_1 to obtain the fraction of the distance between them representing E_1 and therefore an interpolation between these values for the proper value of K .

If the arbitrarily chosen values for K are wrong in the same direction, that is if the value for E_2 and the value of E_3 ultimately arrived at are both higher than or both lower than E_1 the circuit will drop the multiplier for

$$\frac{1}{K}$$

out of the circuit, place the multiplier

$$\frac{1}{K'}$$

into that position in the circuit, that is the voltage obtained by multiplier

$$\frac{1}{K''}$$

will be in line 5, and introduce into the circuit a new value

$$\frac{1}{K'''}$$

which will connect to line 6 producing a new voltage therein. Simultaneously, the circuit calculating the heavier material will drop

$$\frac{1}{K''''}$$

out of the circuit, place

$$\frac{1}{K''''''}$$

into its position and introduce a new value

$$\frac{1}{K'''''''}$$

into the new place previously occupied by

$$\frac{1}{K''''''''}$$

and there will result new voltages E_2 and E_3 which will again be tested by the interpolating circuit to see if one is greater than and one is less than E_1 . This operation may be repeated by each succeeding pair of consecutive

$$\frac{1}{K'''''''''}$$

values in the bank until E_2 and E_3 values bridging E_1 are obtained and the interpolation is made to obtain the proper value of

$$\frac{1}{K''''''''''}$$

Since these values were established for a specific temperature, the ultimately obtained value for

resulting from the interpolation is equivalent to the temperature on the top tray as well as the composition of the liquid. Suitable recording means connected to the interpolating means, such as a teletype machine adapted to record a particular number at a specific rest position of a stepping relay, will be connected to the interpolating means so that the answer ultimately obtained may be preserved as a permanent record.

The apparatus of this invention has to this point calculated the temperature and composition of the liquid on the top tray of the column and it is now desired to calculate the composition of the vapor coming from the second tray down in the column hereinafter called the second tray or, in other words, the vapor coming to the top tray of the column.

It is readily seen that the liquid product from the column, or $\frac{1}{5}$ of the total boil-up from the top tray of the column must pass through the entire column from the feed point to the top tray in the vapor phase. As hereinbefore described, assuming equal molal overflow and equal molal boil-up on each tray, the top tray has, of its five parts of overhead or boil-up, one part lost as product and four parts returning to the tray as reflux. The reflux, or its thermal equivalent, goes to the trays below. It may be seen from this description and from the assumption of equal molal boil-up and equal molal overflow that the mols of liquid passing to any tray is different from the vapor passing from that tray by the number of mols of product.

Therefore, the number of mols of liquid passing from the top tray, the composition of this liquid, and the number of mols of vapor coming from the second tray are all known. By material balance the composition of the vapor can be determined. The composition of the vapor on the second tray is the sum of the ratio of mols of product to mols of boil-up times the product composition plus the ratio of mols of reflux to mols of boil-up times the composition of the liquid from the tray above.

To aid in this explanation, a mathematical analysis of the portion of the column above the feed tray may be made. Making V the mols of vapor passing upwardly through the column, L the mols of liquid passing down, D the mols of product, Y the mol fraction of light material in the vapor and X the mol fraction of light material in the liquid, the following relationships are true:

$$V_2 = L_1 + D$$

where subscripts 1 and 2 indicates the first and second trays. Also, by material balance, this equation, as hereinbefore stated, indicates that the mols of vapor differ from the mols of liquid by the quantity of product.

$$V_2 Y_2 = L_1 X_1 + D X_D$$

By substituting and clearing fractions the equation

$$Y_2 = \frac{L_1}{L_1 + D} X_1 + \frac{D}{L_1 + D} X_D$$

Since the quantity $L_1 + D$ is equal to the boil-up and L_1 is equal to the reflux, in the case of our example where the reflux ratio is four to one, the quantity $L_1 / L_1 + D$ is $\frac{1}{5}$ and the quantity $D / L_1 + D$ is $\frac{4}{5}$.

Thus, in order to determine the composition in light material of the vapor coming to a tray in this example wherein there is a four to one reflux ratio one may add $\frac{1}{5}$ of the composition in light material of the boil-up on the top tray, which is equivalent to the product from the column, to $\frac{4}{5}$ of the composition of light material of the liquid phase on the next higher tray. It may be seen that if the reflux ratio were 1 to 1 the composition difference between the liquid phase on a tray and the vapor phase on the next lower tray would be $\frac{1}{2}$ of the total boil-up from the top tray and if the reflux ratio were 3 to 1 it would be $\frac{1}{4}$, etc.

In the operation of this invention, to obtain the composition of the vapor on the second tray, a voltage dividing means 3 is inserted into the circuit and line 21 carries the voltage taken from this dividing means to a multiplying means which multiplies it by $\frac{1}{5}$, since the reflux ratio is 4 to 1, and transmits this multiplication through line 28 to adding means 30. The voltage dividing means for obtaining this figure will be set to place a voltage in line 21 proportional to the purity of the light material in the product from the column or in this particular case 95 volts. The composition of light material in liquid phase on the first tray is between the voltages in lines 8 and 9 and a close approximation to the true value may be made by using for this value the voltage in the one of these lines which is closest to the true value. Therefore, double throw single pole switch 25 and line 26 are operated by relay or other means connecting to the interpolating circuit 19 so that either line 24 connecting to line 9 or line 23 connecting to line 8 will be used in the circuit depending upon which voltage is closer to the true value of composition. When one or the other is ultimately selected the value of that voltage is transmitted to voltage multiplier 27 which multiplies it by a factor of $\frac{1}{5}$ and transmits the multiplied voltage to voltage adding circuit 30 wherein its value is added to the value previously obtained by multiplying the boil-up on the top tray by $\frac{1}{5}$. This addition, which is the equivalent of adding the amount of overhead product to the liquid passing to the second tray, results in a voltage in line 31 equivalent to the amount of light material in the vapor on the second tray. This voltage is fed into balancing circuit 32 which mechanically establishes the same voltage in line 105 by adjusting the voltage dividing means 101 to produce the desired voltage. By an identical circuit the composition of the vapor phase on the second tray in heavier material is obtained from the second parallel circuit by means of multiplying the voltage in line 34 which is established by placing an initial voltage of 5 volts from potentiometer 4 and multiplying the thus obtained voltage by $\frac{1}{5}$ by multiplying means 35 and feeding that voltage into adding circuit 43 through line 41. This voltage is added to a voltage obtained by multiplying the voltage either in line 16 or in line 15, whichever is closer to the correct answer, through line 37 or 36 and selector switch 38 connected to line 39 and multiplying the thus obtained voltage by $\frac{1}{5}$ through multiplying circuit 40, adding the thus obtained voltage in adding circuit 43 to produce a result equivalent to the composition of the vapor on the second tray in heavy material. This voltage is transmitted by balancing means 45 to voltage dividing means 102 and produces in line 112 a voltage equivalent to that composition.

The voltages in lines 105 and 112 represent the composition of the vapor on the second tray in light material and in heavy material respectively and these lines occupy the same position in an identical circuit as are occupied by lines 5 and 12 in the previously described circuit. Therefore, attaching a circuit to lines 105 and 112 identical to those attached to lines 5 and 12 will produce a calculation that will render the composition of the liquid on the second tray and the composition of the vapor on the third tray. The second circuit in the figure is numbered so that each part in the circuit corresponds to the part in the previously described circuit having a number 100 less. It may be seen that the balancing means 132 and 145 operate to adjust the voltage in lines 5 and 12 so that the circuit used to calculate the first tray is also used to calculate the third tray as well as the fifth tray, the seventh tray, and the ninth tray, etc. until the feed tray is reached at which time the calculations are stopped. The second set of circuits numbered with the 100 series of numbers correspondingly calculate the second tray, the fourth tray, etc. When the composition of either the liquid phase or the vapor phase on a tray is equal to or less in light material than the feed, as heretofore stated

the calculations will be stopped and the apparatus reset to calculate from the bottom tray of the column to the feed tray.

The calculation of the bottom or stripping portion of the column is accomplished by setting the multiplying means 22 and 27 for the light material composition and 35 and 40 for the heavy material composition to conform to conditions in that portion of the column. These calculations are made according to the equation:

$$Y = \frac{L_1}{L_1 - W} X_1 - \frac{W_1}{L_1 - W} X_W$$

where W is the mols of bottoms withdrawn. This equation is derived similarly to the previously used equation and can be found in any competent text book on chemical engineering. The value for L_1 in this equation will be equal to the reflux plus the heavy material in the feed and will generally differ from the value for L_1 used in the stripping or upper portion of the column. At any rate when these values are determined they may readily be set into the apparatus of this invention to calculate the bottom part of the column. The value corresponding to $L_1/L_1 - W$ being placed in multipliers 27 and 40 and the value $W/L_1 - W$ being placed in multipliers 22 and 35. When the multiplying means have been adjusted and the calculations started, the apparatus of this invention will calculate each tray up from the bottom until the feed tray is reached.

Any suitable known or commercially available parts may be used in the assembly of the present invention. The various voltage dividing means that may be used may include potentiometers of the slide wire or stepping relay type, transformers, electronic circuits, etc. The preferred voltage dividing means are potentiometers since their accuracy, simplicity and availability make them well adapted to this function and especially the stepping relay type which are easily actuated by magnetic means. The voltage multiplying means and voltage adding means used may be commercially available circuits which are usually made up as units to be bodily included into the assembly. These units are usually electronic or electro-mechanical circuits such as those shown in Figure 1. 7(a), (b), (c) and (d) of "Electronic Analog Computers," by G. A. and T. M. Korn, first edition published 1952 by McGraw-Hill Publishing Company and since they form no part of this invention except for their function they will not be described in detail herein. The voltage balancing means may be of any suitable type such as a null detector coupled with a slide wire and servo-motor combination or a stepping relay coupled with incremental resistances across each stage. The programming switches may also be stepping relays or other sequencing switches. Interpolating means employed may be a balancing means installed to perform the particular function of balancing the circuit to the constant voltage. For example, a slide wire and servomotor combination may be used to balance the circuit between E_2 and E_3 to be equal to the voltage E_1 . As hereinbefore stated these parts are generally commercially available and it is contemplated that the assembly comprising this invention will be made of any suitable parts which perform these functions.

I claim as my invention:

- An electric computer comprising in combination a constant voltage source connected to a plurality of identical parallel circuits, each of said circuits comprising a first voltage dividing means, adapted to take a portion of said constant voltage, connected to a bank of electrically parallel first voltage multiplying means which are adapted to be preset to specific multipliers, programming means connecting to said first voltage multiplying means adapted to alternately insert pairs of consecutive first multiplying means into an interpolating circuit which contains adding means at opposite sides thereof to add the multiplied voltages to multiplied voltages from the other parallel circuits and bring the circuit to rest at

said constant voltage when one of the sums of the consecutive pairs of first multiplying means causes one voltage greater and one voltage less than said constant voltage, recording means connecting to said interpolating circuit whereby the position of rest of said interpolating circuit is recorded as the difference that said constant voltage is from said greater voltage and said less voltage, second multiplying means adapted to be preset to specific multipliers connected one to a fixed voltage dividing means to multiply the fixed divided voltage and another to multiply the voltage obtained by one of the pair of the aforesaid first multiplying means, a second adding circuit connected to said second multiplying means whereby their voltages are added, balancing means connected to said second adding circuit and to a second voltage dividing means whereby the resultant sum of the voltages is balanced against said constant voltage to obtain a voltage equal to said sum from said second voltage dividing means, means connecting said second voltage dividing means to a bank of parallel third multiplying means which are adapted to be preset to specific multipliers, programing means connected to said multiplying means adapted to alternately insert consecutive pairs of third multiplying means into a second interpolating circuit which contains adding means at opposite ends thereof to add the multiplied voltages to multiplied voltages from the other parallel circuits and bring the circuit to rest at said constant voltage when one of the sums of the consecutive pairs of third multiplying means causes

one voltage greater and one voltage less than said constant voltage, means connecting said second interpolating circuit to said recording means to record the position of rest of said interpolating circuit as the difference that said constant voltage is from said greater and said less voltage, fourth multiplying means adapted to be preset to specific multipliers connected one to said fixed voltage dividing means to multiply the resultant fixed voltage and another to multiply the voltage obtained from one of the pairs of the aforesaid third multiplying means, a fourth adding circuit connected to said fourth multiplying means whereby the voltages are added, balancing means connected to said fourth adding circuit and to said first voltage dividing means whereby the sum of the voltages is balanced against said constant voltage to obtain a voltage from each first voltage dividing means equal to said sum from said voltage dividing means.

2. The computer of claim 1 further characterized in that said banks of parallel multiplying means in each 20 of said parallel circuits, each multiplying means is preset to a value differing from the value of the corresponding multiplying means in each other parallel circuit by an amount proportional to the difference in volatility of the substances to be separated.
